UNITED STATES PATENT OFFICE.

CHARLES F. PYM, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR SHAPING UPPERS OVER LASTS.

Application filed August 13, 1919, Serial No. 317,302. Renewed September 27, 1922. Serial No. 591,000.

To all whom it may concern:

Be it known that I, CHARLES F. PYM, a subject of the King of England, residing at Lynn, in the county of Essex and State of Massachusetts, have invented certain Improvements in Machines for Shaping Uppers Over Lasts, of which the following description, in connection with the accompanying drawings, is a specification, like referring characters on the drawings indicating like parts in the several figures.

This invention relates to machines for shaping uppers over lasts, and more particularly to means for operating on the end portion of a boot or shoe to conform it to the contour of the last or equivalent shoe form. The invention is herein illustrated by reference to its use in a machine for pulling over a shoe and for lasting the toe portion of the shoe; but it is to be understood that the invention in its broader aspects is not restricted in utility to machines for performing both pulling-over and lasting operations nor to mechanism specifically designed for toe lasting.

An object of the invention is to provide an improved construction of end lasting mechanism including end embracing wipers the operation of which is so effected and controlled as to insure uniformly good results irrespective of variations in the character or position of the work. The invention is herein shown as incorporated in a type of machine illustrated in Letters Patent No. 1,436,194 granted upon my application on Nov. 21, 1922; and in one aspect the present invention provides an improvement in lasting mechanism of the general type disclosed in said patent, although it will be recognized that the invention is by no means limited in its applicability to that particular type of machine.

A feature of the invention consists in a novel construction and arrangement of wiper mechanism including wiper closing means which is rendered operative in response to pressure or resistance of the work. In the construction shown closing movement laterally of the shoe is imparted to the wipers in response to resistance encountered by the edges of the wipers upon engagement with the upper materials in their advancing movement lengthwise of the shoe, the wipers being bodily yieldable relatively to their

support which continues its movement and by such movement operates through gearing connections to close the wipers. The wipers are thus self-adjustable to the shoe, and uniform results are insured under varying conditions. In order further to insure uniformity in the action of the wipers upon different portions of the upper materials round the end of the shoe, the invention provides controlling means constructed to cause the wipers to close into substantial conformity to the contour of the edge of the shoe bottom, in response to the resistance encountered, before they become effective with any substantial overwiping action at the end of the shoe, and then to wipe the upper inwardly at the end and at the opposite sides of the end portion of the shoe substantially simultaneously.

Important advantages are involved in the use of the invention in a type of machine like that herein shown in which pulling-over and lasting operations take place in sequence and in which it is of particular importance that the wipers secure effective control of the tensioned upper before the latter is released by the pulling means, and a further feature of the invention consists in the novel combination thus provided.

The above and other features of the invention, including certain details of construction and combinations of parts, will now be more particularly described with reference to the accompanying drawings and pointed out in the claims.

In the drawings,—

Figure 1 is a view in side elevation, and partly in vertical section, of a portion of a machine of the type shown in the patent above mentioned, including toe lasting mechanism constructed in accordance with this invention;

Fig. 2 is a plan view of the toe lasting mechanism detached, with a portion of the structure broken away;

Fig. 3 is an inverted plan view of the mechanism shown in Fig. 2, and

Fig. 4 is a section on the line 4—4 of Fig. 3.

The machine shown comprises grippers for engaging the upper at the toe end of the last and at opposite sides of the forepart, the toe gripper 2 only being shown in the drawings, since it is this gripper which is inti-

2
mately associated wth the lasting mechanism. The shoe is positioned initially in operative relation to the grippers by means of a sole rest 4, an end embracing member 6 which extends round the end face of the last to determine its lengthwise position, and a sole edge holddown member 8 which guards against any upturning of the edge of the sole when the upper is pulled. When the machine is started, the grippers are operated to grip and pull the upper by means of their updraw levers, the toe gripper lever being shown at 10 in Fig. 1, and as the grippers are operated the sole rest 4, together with the members 6 and 8, is swung downwardly a short distance by the action of a cam 12 to supplement the pulling action of the grippers, the heel rest 14 meanwhile being moved upward into supporting position 20 at the heel end of the shoe. The machine then comes automatically to rest with the upper held under tension.

Upon a subsequent starting of the machine shoe clamping and supporting devices 16 are moved into operative relation to the fore part of the shoe and operative movement is imparted to the end lasting mechanism. This mechanism is mounted on the lower end of a front arm 18 pivoted at 20 on the frame of the machine and connected to an operating slide 22 whereby the arm is swung rearwardly a definite distance to cause the lasting mechanism to assume control of the tensioned upper and to perform the lasting operation. The lasting mechanism comprises end embracing wipers 24 which are connected together to swing relatively about a pivot 26, shoe end embracing members 28 mounted on pivots 30 on the lower side of the wipers 40 in position to embrace the end of the shoe and to serve as supports for a lasting binder 32 positioned between these members and the wipers, and driver plates 32 pivotally connected to the wipers and arranged to close 45 inwardly between the wipers and the members 28 to force the binder into holding relation to the upper and to drive its inturned ends into the shoe. Springs 34 arranged to bear oppositely against the members 28 and the driver plates 32 tend to force these members inwardly and the driver plates outwardly to limits determined by pins 36 which are carried by the wipers and engage in slots 38 and 40 formed respectively in the members 28 and the driver plates 32. As the wiper mechanism is moved toward the shoe the members 28 are permitted to yield outwardly against the tension of the springs 34 in conformity to the shape of the shoe and may serve finally to limit the overwiping movement of the wipers. Operative movement is imparted to the driver plates 32 to apply the binder to the shoe and fasten it by means of swinging driver arms 42 connected by links 44 to bell cranks 46, the latter being

operatively connected to the outer end of the slide 22.

The lasting mechanism as a whole is mounted on a support 48 connected by means of a pivot 50 to the lower end of the arm 18 in such manner as to permit the wipers to yield upwardly against abnormal resistance. As the arm 18 is swung rearwardly by the slide 22 the wipers are caused to perform their function as will be hereinafter explained more in detail, the grippers being tripped automatically to cause them to release their hold upon the upper and the members 6 and 8 being withdrawn from operative position to permit the wipers to close over the shoe. The tripping of the toe gripper is effected by engagement of a plate on the arm 18 with a pivoted tripping member 51. When the wipers have arrived substantially at their limit of operative movement, the slide 22 is swung downwardly and operates the driver plates 32 to apply the binder and fasten it, after which the parts are returned to their starting positions and the shoe is released. In these various general features the construction may be and is herein shown as substantially like the construction shown and described in the prior patent to which reference may be made for a more definite understanding of the different details.

For the purposes of this invention, the wipers 24, together with the shoe embracing members 28 and the driver plates 32, are supported on a plate 52 which serves as a wiper carrier and is slidable in guideways formed by downwardly projecting side portions of the supporting bracket 48, the wipers being mounted detachably on gear segments 54 which slide in arc shaped guideways in the plate 52 to determine the path of closing movement of the wipers about their pivot 26. Springs 56 which bear oppositely against the plate 52 and lugs 58 on the bracket 48 tend to move the sliding plate 52 forwardly along its guideways as far as permitted by pins 60 which are fast on the bracket 48 and engage in slots 62 in the plate 52. The gear segments 54 are operatively engaged by pinions 64 mounted to turn about pivots 66 on the plate 52, these pinions being operatively engaged in turn by pinions 68 which are likewise pivotally mounted on the plate 52. In operative engagement with the pinions 68 are rack bars 70 mounted in guideways between the bracket 48 and the plate 52 and normally held in stationary relation to the bracket 48 by means of springs 72 which are adjustably held between set screws 74 in lugs 76 on the bracket and the enlarged outer end portions of the rack bars 70 which have limiting engagement with the edge of the bracket. Mounted also on the plate 52 is a finger 78 which serves as additional means to support

the wire binder and is yieldable backwardly against the resistance of a spring 80 upon its engagement with the end face of the shoe.

- The plate 52 and its supported mechanism 5 are held normally by the springs 56, as shown in the drawings, in an advanced position relatively to the bracket 48, the wipers 24 being held in their outwardly retracted or open position by means of the rack and 10 pinion mechanism hereinbefore described. When operative movement is imparted to the arm 18 to carry the lasting mechanism toward the shoe the parts remain in these relative positions until the wipers come into 15 engagement with the end of the upper which at this time is held by the grippers in tensioned condition. As soon as the resistance of the work thus encountered overcomes the resistance of the comparatively 20 light springs 56, movement of the plate 52 and the wipers lengthwise of the shoe is retarded, and the supporting bracket 48 in its continued movement serves by means of the rack bars 70, which are under the control 25 of the comparatively strong springs 72, to turn the pinions 68 and 64 and thus to impart swinging movement to the gear segments 54 to close the wipers inward laterally of the shoe. Preferably the wipers are 30 positioned normally a sufficient distance in advance of the arm 18 to cause them to be closed into substantial conformity to the contour of the edge of the shoe bottom before the grippers are tripped to release the 35 upper, the closing movement of the wipers into this position being effected under control of the springs 56, prior to any substantial overwiping action of the wipers at the extreme end of the shoe by reason of the 40 comparatively heavy resistance opposed by the tensioned upper to the continued bodily movement of the wipers lengthwise of the shoe. As soon as the wipers have thus been closed about the end of the shoe they begin 45 to close inwardly over the margin of the sole at the opposite sides by reason of continued movement of the support 48 relatively to the plate 52, the decrease in resistance to advancing bodily movement of the wipers 50 upon the release of the upper by the grippers permitting the plate 52 to be advanced gradually at the same time by the increasing tension of the springs 56 and by force transmitted indirectly to said plate from 55 the forward thrust of the rack bars depending upon the resistance encountered by the wipers at the sides of the toe, to cause the wipers to wipe the upper inwardly also at the extreme end of the shoe. Practically 60 therefore the overwiping operation is effected substantially simultaneously at all points round the end portion of the shoe, whether the upper materials are heavy or light in character. If the wipers, however, complete 65 their over-wiping operation at the end of the shoe prior to the completion of their lateral closing movement, the heavy resistance thus encountered limits their further bodily movement lengthwise of the shoe and causes the closing movement of the wipers 70 to be accelerated until they complete the overwiping operation at the sides. If, on the other hand, the wipers are closed inward laterally of the shoe as far as permitted by the shoulder of the sole or by the members 75 28 before completing their operative movement at the end of the shoe, the springs 72 permit a relative yield between the bracket 48 and the rack bars 70 and thus permit the wipers to advance without further closing 80 movement or even to be forced laterally outward against the tension of these springs by the resistance of the shoe materials. When the arm 18 receives its outward return movement after the overwiping and fastening operations have been performed, the springs 56 react and return the plate 52 and the wipers to their starting positions 85 illustrated in the drawings.

While the invention is herein illustrated 90 by reference to its use in the manufacture of a turn shoe, it will be understood that it is not limited in utility to the manufacture of shoes of this particular type.

Having described the invention, what I 95 claim as new and desire to secure by Letters Patent of the United States is:

1. In a machine of the class described, the combination with shoe positioning means, of end embracing wipers mounted for closing 100 movement laterally of the shoe, means for moving said wipers bodily lengthwise of the shoe to operate them, and closing mechanisms for the respective wipers operative each independently of the other in response to the resistance to said lengthwise movement of the wipers encountered by engagement of the wipers with the shoe materials to impart to said wipers their lateral closing movement. 105

2. In a machine of the class described, the combination with shoe positioning means, of a wiper support, means for moving said support lengthwise of the shoe, end embracing wipers movably mounted on said support to 115 permit the support to move relatively to the wipers lengthwise of the shoe in response to resistance to the advancing movement of the wipers encountered by engagement of the wipers with the shoe materials, said wipers being also mounted for closing movement laterally of the shoe, and means operated by the movement of the support relatively to the wipers in response to resistance encountered by the edges of the wipers to impart 120 lateral closing movement to the wipers. 125

3. In a machine of the class described, the combination with shoe positioning means, of a wiper support, means for moving said support lengthwise of the shoe, end embracing 130

wipers movably mounted on said support to permit the support to move relatively to the wipers lengthwise of the shoe in response to resistance to the advancing movement of the 5 wipers encountered by engagement of the wipers with the shoe materials, the wipers being also mounted for closing movement laterally of the shoe, means operated by the movement of the wiper support relatively 10 to the wipers to impart said lateral closing movement to the wipers, and yielding means for controlling the relative movement between the wipers and the wiper support constructed and arranged to cause the wipers to 15 be closed inwardly into substantial conformity to the contour of the edge of the shoe bottom in response to the resistance to their advancing movement prior to any substantial overwiping action of the wipers at the end of 20 the shoe.

4. In a machine of the class described, the combination with shoe positioning means, of end embracing wipers mounted for bodily movement lengthwise of the shoe and also 25 for closing movement laterally of the shoe, and independent gearing connections for the different respective wipers operative in response to resistance to advancing movement of the wipers encountered by engagement of 30 the edges of the wipers with the shoe materials to close the wipers inwardly into substantial conformity to the contour of the edge of the shoe bottom prior to any substantial overwiping action at the extreme end of the 35 shoe and then to close them farther inwardly during their overwiping action at the end of the shoe.

5. In a machine of the class described, the combination with shoe positioning means, of 40 end embracing wipers mounted for closing movement laterally of the shoe, means for moving said wipers bodily lengthwise of the shoe, closing mechanisms for the different respective wipers operative each independently 45 of the other in response to resistance encountered by the edges of the wipers in said lengthwise movement to close them inward laterally of the shoe, and controlling means to cause the wipers to be closed into substantial 50 conformity to the contour of the edge of the shoe bottom in response to such resistance before they become effective with any substantial overwiping action at the end of the shoe and then to wipe the upper inward at 55 the end and the opposite sides of the end portion of the shoe substantially simultaneously.

6. In a machine of the class described, the combination with shoe positioning means, of 60 end embracing wipers mounted for closing movement laterally of the shoe, means for effecting relative movement of said shoe positioning means and wipers in a direction lengthwise of the shoe to cause the wipers to 65 operate on the shoe, and closing connections

for the different respective wipers operative each independently of the other in response to the resistance to such relative movement encountered by engagement of the edges of the wipers with the shoe to impart to the 70 wipers their lateral closing movement.

7. In a machine of the class described, the combination with shoe positioning means, of a wiper support, end embracing wipers on said support mounted for closing movement 75 laterally of the shoe, means for effecting relative movement of said shoe positioning means and wiper support in a direction lengthwise of the shoe to cause the wipers to operate on the shoe, the wipers being bodily yieldable relatively to the support in response to resistance encountered by their engagement with the shoe, and means responsive to such yield of the wipers to impart to them their lateral closing movement. 80

8. In a machine of the class described, the combination with shoe positioning means, of end embracing wipers mounted for closing movement laterally of the shoe, means for moving said wipers bodily lengthwise of the 85 shoe to operate them, controlling means to permit said wipers to yield bodily against advancing movement lengthwise of the shoe in response to resistance of the shoe materials and then to continue their advancing movement as the resistance is overcome, and intermeshing toothed members relatively movable in response to such bodily yield of the wipers to impart to said wipers their lateral closing 90 movement. 95

9. In a machine of the class described, the combination with shoe positioning means, of a wiper support, means for moving said support lengthwise of the shoe, a wiper carrier mounted on said support to permit relative 105 movement between the support and said carrier in directions lengthwise of the shoe, end embracing wipers mounted on said carrier for closing movement laterally of the shoe, and gearing connections operated by movement of said support relatively to the wiper carrier as the support is moved toward the shoe to impart lateral closing movement to the wipers. 110

10. In a machine of the class described, 115 the combination with shoe positioning means, of end embracing wipers mounted for bodily advancing movement lengthwise of the shoe and also for closing movement laterally of the shoe, and rack and pinion mechanism comprising intermeshing toothed members relatively movable in response to resistance of the work to said bodily movement of the wipers to impart lateral closing movement to the wipers. 120

11. In a machine of the class described, the combination with shoe positioning means, of end embracing wipers mounted for bodily advancing movement lengthwise of the shoe and also for closing movement later- 125 130

ally of the shoe, and gearing connections comprising intermeshing toothed members relatively movable in response to resistance encountered by the wipers in engagement 5 with the shoe to impart lateral closing movement to the wipers.

12. In a machine of the class described, the combination with shoe positioning means, of end embracing wipers mounted for bodily movement lengthwise of the shoe and also for closing movement laterally of the shoe, rack and pinion mechanism comprising intermeshing toothed members relatively movable in response to resistance of the 15 work to said bodily movement of the wipers to impart lateral closing movement to the wipers, and controlling means for said mechanism to cause the wipers to be closed inwardly into substantial conformity to the 20 contour of the edge of the shoe bottom prior to any substantial overwiping action at the end of the shoe.

13. In a machine of the class described, the combination with shoe positioning means, 25 of a wiper support, end embracing wipers movably mounted on said support to permit relative movement between the support and the wipers in a direction lengthwise of the shoe in response to resistance of the shoe 30 materials, said wipers being also mounted for closing movement laterally of the shoe, and gearing connections operated by said relative movement between the support and the wipers to impart the lateral closing 35 movement to the wipers.

14. In a machine of the class described, the combination with shoe positioning means, of a wiper support, means for moving said support lengthwise of the shoe, a wiper carrier movably mounted on said support to permit the support to move relatively to the carrier lengthwise of the shoe in response to resistance of the work to the movement of the carrier, end embracing wipers mounted 40 on said carrier for closing movement laterally of the shoe, pinions mounted on said carrier and connected to the wipers, and means operated by said movement of the support relatively to the wiper carrier to turn said pinions and impart lateral closing 45 movement to the wipers.

15. In a machine of the class described, the combination with shoe positioning means, of a wiper support, means for moving said support lengthwise of the shoe, a wiper carrier movably mounted on said support to permit the support to move relatively to the carrier lengthwise of the shoe in response to resistance of the work to the movement of 55 the carrier, end embracing wipers mounted on said carrier for closing movement laterally of the shoe, pinions mounted on said carrier and connected to the wipers to impart closing movement to the wipers, and 60 rack bars on said support connected to said

pinions to operate them through the movement of the support relatively to the carrier.

16. In a machine of the class described, the combination with shoe positioning means, of a wiper support, means for moving said support lengthwise of the shoe, a wiper carrier movably mounted on said support to permit the support to move relatively to the carrier lengthwise of the shoe in response to resistance of the work to the movement of 70 the carrier, end embracing wipers mounted on said carrier for closing movement laterally of the shoe, pinions mounted on said carrier and connected to the wipers to impart closing movement to the wipers, rack 75 bars on the support connected to said pinions to operate them through the movement of the support relatively to the carrier, and spring means for holding said rack bars normally in stationary relation to said support while permitting them to yield in response to resistance to closing movement of 80 the wipers.

17. In a machine of the class described, the combination with shoe positioning means, 90 of end embracing wipers mounted for relative closing movement laterally of the shoe, pinions connected to said wipers, rack bars connected to the pinions, and means for moving said rack bars lengthwise of the shoe 95 to turn the pinions and impart closing movement to the wipers.

18. In a machine of the class described, the combination with shoe positioning means, of a wiper support movable lengthwise of the shoe, a wiper carrier movably mounted on said support, end bracing wipers mounted on said carrier for closing movement laterally of the shoe, spring means between said support and carrier to render the carrier yieldable against advancing movement in response to resistance encountered by the edges of the wipers, and connections between said support and carrier responsive to such yield of the carrier to impart lateral 100 closing movement to the wipers.

19. In a machine of the class described, the combination with shoe positioning means, of a wiper support movable lengthwise of the shoe, a wiper carrier movably mounted on said support, end bracing wipers mounted on said carrier for closing movement laterally of the shoe, yielding means for normally maintaining said carrier in an advanced position relatively to the support 115 while permitting the carrier to yield against advancing movement in response to resistance of the work, and gearing connections between said support and carrier for imparting lateral closing movement to the wipers proportional to the extent of relative movement of the support and the carrier as the carrier yields.

20. In a machine of the class described, the combination with shoe positioning 120

means, of a wiper support movable lengthwise of the shoe, a wiper carrier movably mounted on said support, and embracing wipers mounted on said carrier for closing movement laterally of the shoe, yielding means for normally maintaining said carrier in an advanced position relatively to the support while permitting the carrier to yield against advancing movement in response to resistance of the work, and means dependent upon resistance encountered by the wipers in engagement with the shoe for imparting lateral closing movement to the wipers proportional to the extent of such relative movement of the support and the carrier as the carrier yields, said yielding means being so constructed to control the closing movement of the wipers as to cause them to wipe the upper inwardly at the end and the sides substantially simultaneously.

21. In a machine of the class described, the combination with last and upper positioning means, of means for pulling the upper over the last and for holding it under tension, and embracing wipers mounted for bodily movement lengthwise of the shoe and for closing movement laterally of the shoe to wipe the upper into lasted position, means responsive to resistance encountered by the wipers upon their engagement with the tensioned upper held by the pulling means for imparting lateral closing movement to the wipers, and means operative in time relation to the operative movement of the wipers to cause said upper pulling means to release the upper.

22. In a machine of the class described, the combination with last and upper

positioning means, of means for pulling the upper over the last and for holding it under tension, a wiper support mounted for movement lengthwise of the shoe, and embracing wipers carried by said support and arranged to yield against advancing movement as their edges encounter the resistance of the upper held by the pulling means and to advance farther for wiping the upper inwardly at the end of the shoe when said resistance is removed, means operated by continued movement of the wiper support upon such yield of the wipers to close the wipers inward laterally of the shoe, and means for causing said upper pulling means to release the upper when the wipers have been closed into substantial conformity to the contour of the edge of the shoe bottom.

23. In a machine of the class described, the combination with last and upper positioning means, of means for pulling the upper over the last and holding it under tension, a wiper support mounted for movement lengthwise of the shoe, a wiper carrier movably mounted on said support and arranged to yield in response to resistance of the work, and embracing wipers mounted on said carrier for closing movement laterally of the shoe, gearing connections between said support and carrier for closing the wipers in response to yield of the carrier, and means operative in time relation to the movement of the wipers to cause the upper pulling means to release the upper.

In testimony whereof I have signed my name to this specification.

CHARLES F. PYM.
